UNITED STATES PATENT OFFICE.

JOSEPH WEBB, OF BEAVER, PENNSYLVANIA.

DESIGN FOR A LAMP GLOBE OR SHADE.

SPECIFICATION forming part of Design No. 16,419, dated December 15, 1885.

Application filed November 4, 1885. Serial No. 181,866. Term of patent 7 years.

To all whom it may concern:

Be it known that I, JOSEPH WEBB, a citizen of England, residing at Beaver, in the county of Beaver and State of Pennsylvania, have invented certain new and useful Improvements in Designs for Glass Globes or Shades; and I do hereby declare the following to be a full, clear, and exact description of the invention, reference being had to the accompanying drawings, which form part of this specification.

This invention has relation to designs for lamp or gas globes, shades, and like articles; and it consists of the ornamental configuration hereinafter described, and shown in the accompanying drawing.

The drawing represents what is popularly known as the "Grecian" pattern of lamp-shades; and the design consists in the diagonal fluting or pillars B B running from the upper edge to the base and in curves of ogee

shape. The fluting or pillars are close together, and constitute the entire surface ornamentation. The lines or grooves between the pillars converge at their extremities in keeping or conformity with the shape of the shade.

This design is applicable to other patterns of shades besides the one shown in the drawing.

What I claim as my design is—

The design for shades or globes, consisting of the substantially-globular body having the rounded pillars B B, extending diagonally from the top to the bottom of the globe, substantially as shown and described.

In testimony that I claim the foregoing I have hereunto set my hand this 2d day of November, 1885.

JOSEPH WEBB.
